(73) **Assignee:** **3M Innovative Properties Company**, St. Paul, MN (US)*Primary Examiner* — Eric L Goodman*Assistant Examiner* — Lilyana Bekic(**) **Term:** **15 Years****CLAIM**(21) **Appl. No.:** **29/577,882**

The ornamental design for a valve cover with openings, as shown and described.

(22) **Filed:** **Sep. 16, 2016****DESCRIPTION**(51) **LOC (11) Cl.** **29-02**

U.S. application Ser. No. 29/577,873 filed on the same date as the present application, entitled "Valve Cover," is incorporated herein by reference in its entirety.

(52) **U.S. Cl.**

FIG. 1 is a right top perspective view of a valve cover with openings in accordance with our new design;

USPC **D24/110.6; D24/127**

FIG. 2 is a top plan view thereof;

(58) **Field of Classification Search**

FIG. 3 is a front elevation view thereof;

USPC D24/110.1, 110.6, 162, 127, 129;

FIG. 4 is a rear elevation view thereof;

D23/332, 335, 355, 356, 366, 388, 412;

FIG. 5 is a left side elevation view thereof, the right side elevation view is a mirror image thereof;

D29/102, 105, 106

FIG. 6 is a bottom plan view thereof;

CPC A62B 18/025; A62B 18/02; A62B 9/02;

FIG. 7 is a right top perspective view thereof and shown attached to a base; and,

A62B 18/084; A62B 23/02; A62B 7/10;

FIG. 8 is a right top perspective view of FIG. 7 and shown attached to a respirator.

A62B 18/08; A61M 16/208; A61M 16/201;

The right side elevation view of the design of FIG. 1 is a mirror image of the left side elevation view illustrated in FIG. 5.

A61M 16/20; A61M 16/06; A61M 16/0003; A61M 16/206

The broken line showing of the base in FIGS. 7-8 and the respirator in FIG. 8 depict environment and form no part of the claimed design. All other broken lines depict portions of the valve cover with openings that form no part of the claimed design.

See application file for complete search history.
